UNITED STATES PATENT OFFICE.

NILS RICHARD FORSSBLAD, OF VÄSTERÅS, SWEDEN.

ELECTRICAL STEAM AND HOT-WATER BOILER.

1,386,487.

Specification of Letters Patent.

Patented Aug. 2, 1921.

Application filed June 10, 1920. Serial No. 388,033.

To all whom it may concern:

Be it known that I, NILS RICHARD FORSSBLAD, civil engineer, subject of the King of Sweden, residing at Västerås, in the Kingdom of Sweden, have invented certain new and useful Improvements in Electrical Steam and Hot-Water Boilers, (for which I have filed an application in Sweden, Nov. 14, 1918,) of which the following is a specification.

The present invention relates to such steam- or hot water boilers in which the steam is produced by an electrical current passing directly between electrodes sub-merged in the water.

In all boilers of the type herein considered the electrodes will have to be surrounded by tubes of some insulating material, in order to prevent direct short circuits between the electrodes. The control of the output, which is generally wanted, was heretofore obtained mostly by disconnecting one or more electrodes by means of a plurality of switches arranged outside the boiler.

According to the present invention the control of the output is effected by raising or lowering the insulating tubes surrounding the electrodes, whereby the length and thereby the resistance of the water columns within the tubes is varied. By this arrangement the output of the boiler may thus be varied within certain limits without changing the number of electrodes connected in circuit. Therefore, the number of electrodes answering certain requirements for control need not be as large as in the constructions heretofore employed, and this, evidently, contributes to a reduction of the costs for the boiler as compared with prior systems.

Two embodiments of the boiler are illustrated in the accompanying drawing, wherein—

Figures 1-3 show an upright boiler with six electrodes, while Figs. 4 and 5 disclose a horizontal boiler with three electrodes. Fig. 1 is a vertical section on line A—A, and Fig. 2 a vertical section on line B—B in Fig. 3. Fig. 3 is a horizontal section on line C—C in Fig. 1. Figs. 4 and 5 are similar longitudinal- and cross sections respectively.

The shell of the boiler is designated by 1. The numeral 2 denotes the electrodes, 3 the inlet ducts, 4 the insulating tubes and 5 a contrivance for keeping these tubes together. 6 are ropes by means of which the

tubes may be raised and 7 is a hoisting device for the ropes, such device consisting of a rotatable shaft and operating means in the form of a hand wheel. Arrangements other than the one herein disclosed may obviously be used for raising and lowering the pipes 4, such arrangements comprising for example devices operated by tooth racks or levers.

The mode of operation of the boiler is as follows: The electrical current, preferably a multiphase alternating current, is led into the boiler at the lower side thereof through the inlet ducts 3 and to the electrodes 2, and the current then passes through the water between the electrodes. According as the tubes 4 are raised or lowered by means of the ropes 6 and the shaft 7, the resistance of the water between the electrodes varies, and consequently also the output of the boiler varies.

The electrodes may be of any form suitable for the purpose but preferably they are ball-shaped. Generally, they should have a relatively short length in the longitudinal direction of the surrounding tube.

The tubes are preferably open at both ends, so as to allow of a free circulation of the water and to allow the circuit to be closed in both directions through the tube.

If desired, the electrodes may be introduced from the top or from the side of the boiler, and the insulating tubes 4 and the inlet ducts 3, or the ends thereof, may also be arranged in a slanting position.

The same arrangements for control may evidently be used also in boilers employed only for the purpose of heating water.

What I claim as new and desire to secure by Letters Patent of the United States is:—

1. A method of controlling the output of electrical steam or hot water boilers of the type wherein the heat is produced by passing an electric current through the water between submerged electrodes each surrounded by an insulating tube, consisting in varying the length of the inclosed columns of water passed by the current by displacing the tubes axially relatively to the electrodes.

2. An arrangement for controlling the output of electrical steam or hot water boilers comprising a plurality of submerged electrodes arranged within the water in the boiler, an insulating tube surrounding each of said electrodes, and means for varying the length of the inclosed columns of water

- passed by the current and including mechanism for displacing the tubes axially relatively to the electrodes.
3. An arrangement of the kind defined by claim 2 in which the electrodes are fixed and in which the tubes are displaceable in a longitudinal direction.
4. An arrangement of the kind defined by claim 2 in which the tube displacing means 10 comprises a rotatable shaft extending through the boiler and provided with operating means whereby the tubes may be moved from the exterior of the boiler by rotating said shaft.
5. An arrangement of the kind defined by claim 2 in which the electrodes are open at both ends.
6. An arrangement as claimed in claim 2 in which the active parts of the electrodes are of substantially ball-shape and of relatively short length.

In testimony whereof I affix my signature in presence of two witnesses.

NILS RICHARD FORSSBLAD.
